UNITED STATES PATENT OFFICE.

FRANK G. HIGGINS, OF SPOKANE, WASHINGTON.

CATAMENIAL BANDAGE.

1,342,588.

Specification of Letters Patent.

Patented June 8, 1920.

Application filed April 22, 1919. Serial No. 291,959.

To all whom it may concern:

Be it known that I, FRANK G. HIGGINS, a citizen of the United States, residing at Spokane, in the county of Spokane and 5 State of Washington, have invented certain new and useful Improvements in Catamenial Bandages, of which the following is a specification.

The present invention relates to improvements in catamenial bandages, and is designed to provide a comfortable and sanitary device of this character that may readily be adjusted to fit the body of the wearer, and may with facility be changed as necessity requires. To this end the invention, in 10 its physical embodiment, comprises a bandage made preferably from moisture proof fabric and supported from a waist belt, and combined with straps and tapes that permit 15 of the required adjustability and arranged so that the bandage carrying the napkin may with facility be detached or unfastened when required, and then quickly and conveniently attached again for use.

20 In the accompanying drawings one complete example of the physical embodiment of the invention is illustrated according to the best mode so far devised for the practical application of the principles of the invention, and which embodiment has proven 25 highly successful in actual practice.

Figure 1 is a front perspective view of the device.

Fig. 2 is a rear perspective view of the 30 same device.

Fig. 3 is an enlarged, plan view of the under side of the bandage and the attaching pad, the two tabs to which the napkin is to be attached being shown in dotted lines.

40 In the preferred form of the invention as depicted in the drawings, a waist belt 1 is utilized, being comprised of suitable fabric and made to conform to the shape of the figure, and preferably connected at the front 45 by the lace indicated at 2.

The bandage 3 is made of moisture proof fabric and shaped for comfort and convenience, the wide body portion of the bandage at the rear being fashioned with a narrower extension 4 curved to proper shape, and the two tapes or tabs 5 and 6 shown in dotted lines in Fig. 3 are provided to which the napkin is to be attached, as by safety pins.

An abdominal pad or support 7 is utilized, and this pad forming the front portion of the catamenial device is detachably connected with the bandage by a series of elastic straps indicated as 8 (there being three shown) which are preferably formed 55 with button holes 9 to fasten over the buttons 10 sewed to the pad. The elasticity of these three connecting straps of course permits of adjustment and the presence of the two (or more) sets of button holes enables 60 the wearer to adjust the device for comfort and effective use of the bandage. It will readily be apparent that the three straps may be slipped from their buttons, the napkins changed, and the bandage replaced and 65 buttoned to the pad with convenience and facility, without the discomfort and annoyance of any further alterations or adjustments in the parts of the device.

The device is supported from the waist of 70 the wearer by four elastic straps over the hips, two front straps 11 being indicated and two rear straps 12 being shown in the two perspective views. A front strap 11 and a rear strap 12 are arranged at each hip 75 and they join the belt at diametrical opposite points, in pairs. Each strap is provided with an adjustable buckle 13 for varying the length of the strap, and attachment to the bandage or pad is made through one of the 80 reinforcing tabs 6' or 7' sewed to the bandage or pad as the case may be, it being preferable, however, that loops 14 be utilized in making the direct connection between the parts, to lend flexibility and adaptability to 85 the device.

To the sides of the rear portion 3 of the bandage are attached the thigh straps 15, which, like the hip straps, are of elastic material, and these straps pass around the 90 thighs and are attached to the pad 7 at the front, buckles 13 and loops 14 also being used as in the case with the hip straps.

From the above description taken in connection with the drawings it is apparent 100 that a comfortable, convenient and sanitary device is provided that may be manipulated with facility, and it will especially be noted that there is an absence of devices, buckles or fastenings, usually found in connection 105 with these bandages and shoved up under the corsets. The arrangement of the parts allows for a wide adjustability thereof in

adapting the device for varying figures, and the easy attachment and detachment of the parts renders the device of enhanced value.

Claim:

5 A device of the character described, comprising a substantially horizontal abdominal pad of a substantial length having its ends projecting over the legs of the user, a waist-belt arranged above and spaced from
10 the pad, upper front straps secured to the upper corners of the pad and diverging upwardly for connection with the belt near diametrically opposite points, a bandage forming a napkin shield, said bandage having a rear elongated horizontal rectangular

portion provided with a forwardly projecting reduced portion having the rear portion of its longitudinal edges curved, upper rear straps secured to the upper corners of the bandage and diverging upwardly for connection with the belt near said diametrically opposite points, horizontal straps connected with the lower corners of the pad and the bandage, and a plurality of elastic bands connected with the free end of the reduced extension and having detachable engagement with the lower edge of the pad.

In testimony whereof I affix my signature.

FRANK G. HIGGINS.
